UNITED STATES PATENT OFFICE.

ABRAM FRANK PAUL, OF LLANERCH, PENNSYLVANIA, ASSIGNOR TO NATIONAL PNEUMATIC COMPANY, OF NEW YORK, N. Y., A CORPORATION OF WEST VIRGINIA.

PUSH-BUTTON APPARATUS FOR MULTIPLE-UNIT DOOR-CONTROL SYSTEMS.

Application filed December 17, 1921. Serial No. 523,077.

This invention relates to push button control apparatus for multiple unit door control systems.

The object of the invention is to provide a push button control system of the nature and for the purpose referred to which is simple in structure and efficient in operation, and wherein a plurality of push buttons may be selectively and individually operated, or may be collectively operated according to the exigencies of use.

The invention consists substantially in the construction, combination, location and relative arrangement of parts, all as will be more fully hereinafter set forth, as shown in the accompanying drawings and finally pointed out in the appended claims.

Referring to the drawings:

Fig. 1 is a view in front elevation with some parts broken away showing a slightly modified arrangement embodying the principles of my invention.

Fig. 2 is a view in transverse section on the line 4—4, Fig. 1, looking in the direction of the arrows.

Fig. 3 is a view similar to Fig. 1 showing modified forms of push button control apparatus.

Fig. 4 is a view similar to Fig. 1 showing another modified arrangement embodying the principles of my invention.

Fig. 5 is a view in vertical section on the line 7—7, Fig. 4, looking in the direction of the arrows.

Fig. 6 is a view similar to Fig. 1 and partly in section on the line 8—8, Fig. 7, showing still a further slightly modified arrangement.

Fig. 7 is a view in transverse section on the line 9—9, Fig. 6, looking in the direction of the arrows.

Fig. 8 is a view of another modification.

In the modern multiple unit door control system for use on cars or trains of cars, particularly cars or trains employed in surface, subway and elevated street car transporting systems, it is a common practice to employ push buttons for controlling the circuits of the motors by which the car doors are operated. In such systems the control of a number of doors on a car or train of cars is located at a control point or station, and for effective control of the car operating motors it is sometimes desirable to be able to selectively operate or control the

operation of the door operating motor of the individual doors. At other times it is desirable to be able to simultaneously operate or control the operation of all of the door operating motors on any particular car or on several cars.

It is among the special purposes of my present invention to provide a push button control apparatus which enables the selective operation of individual push buttons controlling the car door operating motors for individual doors and which apparatus is also capable of group operation simultaneously of a plurality of the push buttons thereby enabling an operator at the control station to operate or control any particular car door operating motor or, at will, simultaneously controlling the push buttons in the circuits of a plurality of door motors.

In the accompanying drawings I have shown various arrangements embodying the general principles of a push button control apparatus which permits such selective operation of individual push buttons and also a simultaneous operation of circuit closures for a group or a number of motor circuits.

In Figs. 1 and 2 I have shown an arrangement wherein the circuit terminals 11 are controlled by the individual push buttons 12 operating the bridging contact member 14. The master push button 20, mounted in the control case 21, when actuated, engages an arm 22 connected to a shaft 23. This shaft is journaled within the casing 21 and carries a number of crank arms 24, each carrying a bridging contact member 25 each disposed in cooperative relation with respect to a pair of circuit terminals 11. When the master push button 20 is manipulated the shaft 23 is rocked thereby causing the crank arms 24 thereon to move the contactors 25 into contact with their respective pairs of terminals 11, hence securing a simultaneous closing of all of the circuits, the terminals of which lead into the box, leaving the operator or attendant, however, free to independently and selectively operate any individual push button 12. The contactors 25 may be returned to their withdrawn position in any suitable manner. I have shown in this instance a retracting spring 26 for this purpose (see Fig. 2).

In Fig. 3 I have shown two modified arrangements, the one in the upper part of the figure consisting of a master push button

27 normally held retracted by the spring 28, and having a rod 29 connected to the push button to be projected endwise when the push button is pushed. A plurality of contactor members 30 is hinged within the casing 31, as at 32, the free ends of said contactors being engaged by the rod 29 so that when the master push button 27 is depressed all of the contactors 30 are moved into position simultaneously to close the circuit between their respective pairs of terminals 33. This leaves each pair of terminals 33 to be bridged independently and individually by the usual push buttons indicated in dotted lines at 34. In the lower part of Fig. 3 a master push button 35 is shown for projecting longitudinally a rod 36 which, when projected endwise, effects the rocking of the plurality of contactor arms 37 through link connections, indicated at 38, with the rod 36, or by means of pins 39, carried by the rod and engaging the contactor arms. Thus, by the pressing of the push button 35 the various pairs of terminals 39 are closed by their respective contactor arms 37, the closure being simultaneous as to all of the pairs of circuit terminals 39, leaving each pair of terminals free to be closed through the usual and ordinary push button indicated in dotted lines at 40.

30 In Figs. 4 and 5 a slightly modified arrangement is shown wherein the master push button 41 effects the rocking of the rocked shaft 42 through the link and crank arm connections 43, said shaft 42, which is journaled to rock within the casing 44, has crank arms 45 thereon which carry contactor members 46 disposed in such relation with respect to the terminals 47 as to close the circuit between them when the shaft 42 is rocked by the manipulation of push button 41. This leaves the terminals 39 to be individually and selectively closed by the manipulation of the usual and ordinary push button 48 carrying contactor bars 49.

45 In Figs. 6 and 7 I have shown the master control button 50 as operating a bar 51 disposed to extend crosswise of the various pairs of terminals 52 and beneath the same so that the contactors 53, carried thereby, may be withdrawn from bridging contact with the pairs of terminals 52 by the action of gravity. This arrangement leaves each pair of terminals 52 to be selectively and individ-

ually closed to each other by the ordinary push button 54 and its bridging contactor 55.

5 In Fig. 8 I have shown a modified form of my invention which is very simple in construction, yet is exceedingly desirable and effective in operation. In this type of construction the master control button 56 is integrally attached to the operating bar 57, which bar carries a plurality of springs 58, and contactors 59, for closing all the circuits when the master control button is pushed in and the terminals 11 become engaged. Each pair of terminals 11 may also be closed by a separate push button 12, for actuating contactors 14 in the manner shown and described in connection with Figs. 1, 2, 3 and 4.

6 From the foregoing description it will be seen that I provide in various practical simple embodiments the push button control system which permits the selective and individual control of the actuating motors of individual doors and at the same time permits of simultaneous control of the motors of a plurality or group of door motors.

7 Having now set forth the objects and nature of my invention and various constructions embodying the principles thereof, what I claim as new and useful and of my own invention and desire to secure by Letters Patent, is:

1. In a multiple circuit control device the combination of a plurality of circuit terminals, independent means for closing the circuit to each individual pair of contacts, a rod having a plurality of contact fingers thereon for simultaneously closing the circuits to each individual pair of contacts, and independent means to operate said rod to close the circuits.

8 2. In a multiple circuit control device the combination of a plurality of circuit terminals, independent means for closing the circuit to each individual pair of contacts, a rod having a plurality of arms rigidly secured thereto, adapted to close all the circuits simultaneously when the rod is rotated, and means to rotate said rod.

9 In testimony whereof I have hereunto set my hand on this 14th day of September A. D., 1921.

A. FRANK PAUL.
